LAVATORY FAUCET SHELL

Stephen A. Young, Monticello, Ind. (Flora, Ind.)

Filed Dec. 1, 1960, Ser. No. 63,064

Term of patent 14 years

(Cl. D91—3)

FIGURE 1 is a front elevation of a lavatory faucet shell embodying my new design.

FIGURE 2 is a side elevation of the same.

FIGURE 3 is a top plan view of the same.

FIGURE 4 is a rear elevational view of the same.

FIGURE 5 is a bottom plan view of the same.

I claim:

The ornamental design for a lavatory faucet shell, substantially as shown.
